UNITED STATES PATENT OFFICE.

SAMUEL J. LARGE, OF BRISTOL, CONNECTICUT, ASSIGNOR TO THE BRISTOL
BRASS AND CLOCK COMPANY, OF SAME PLACE.

DESIGN FOR A SPOON OR FORK HANDLE.

SPECIFICATION forming part of Design No. 32,561, dated April 24, 1900.
Application filed March 31, 1900. Serial No. 11,022. Term of patent 7 years.

To all whom it may concern:

Be it known that I, SAMUEL J. LARGE, a citizen of the United States, residing at Bristol, in the county of Hartford and State of Connecticut, have invented and produced a new and original Design for Spoon or Fork Handles, of which the following is a specification, reference being had to the accompanying drawings, forming part thereof.

Figure 1 is a plan view of a spoon-handle, showing my design. Fig. 2 is a reverse plan of the same.

As shown in the drawings, the contour of the handle is formed of compound-curved lines arranged as shown. On the front or upper side, at the smaller end, there are two scroll ornaments 3 3 and leaflets 4 4 outside the upper portions of the scrolls 3 3. Above the scrolls 3 3 there are two inwardly-turned scroll ornaments 5 5, that merge into the border beads or ribs 6 6 and extend nearly to the upper end of the handle, the said beads terminating in larger scroll ornaments 7 7. Inside of the border-beads 6 6 there are two other

finer beads 8 8, the upper ends of which roll 25 inwardly until they nearly meet. Above the beads 6 6 and 8 8 there is a series of scroll-leaflets arranged as shown and covering the tip at the other end of the handle.

The reverse or back side of the handle has 30 at its smaller end scroll-leaflets 3^a 3^a at each edge, and then the two series of ribs or beads 6^a 6^a and 8^a 8^a; but the latter do not curve in so far at their upper ends as do the corresponding beads on the front side. There is a U- 35 shaped border-bead 9 at the tip of the handle and a scroll-leaflet 10 at each end thereof, with the three ornaments 11 11 12 inside of the said bead and leaflet 9 10, as shown.

Having described my invention, what I 40 claim as new, and desire to secure by Letters Patent, is—

The design for a spoon or fork handle, as herein shown and described.

SAMUEL J. LARGE.
